US00D682836S

(12) **United States Design Patent**
Akana et al.

(10) **Patent No.:** US D682,836 S
(45) **Date of Patent:** ** May 21, 2013

(54) **COVER**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/425,618**

(22) Filed: **Jun. 25, 2012**

Related U.S. Application Data

(63) Continuation of application No. 29/384,903, filed on Feb. 4, 2011, now Pat. No. Des. 663,304, which is a continuation-in-part of application No. 29/375,197, filed on Sep. 17, 2010, now Pat. No. Des. 658,186.

(57) CLAIM

The ornamental design for a cover, as shown and described.

DESCRIPTION

FIG. 1 is a front perspective view of a cover showing our new design;

FIG. 2 is a rear perspective view thereof;

FIG. 3 is a front view thereof;

FIG. 4 is a rear view thereof;

FIG. 5 is a bottom view thereof;

FIG. 6 is a top view thereof; and,

FIG. 7 is a side view thereof, the opposite side being a mirror image thereof.

Broken lines and portions contained within broken lines are not claimed.

Solid lines and the portions contained within solid lines comprise the claim.
